TOOL AND HANDLE ATTACHING MEANS
THEREFOR

Christopher D. Budelman, Baldwin, N. Y.

Application April 2, 1947, Serial No. 738,873

9 Claims. (Cl. 306—35)

1

This invention relates to tools, especially tools such as a hammer or an ax, and more particularly to means for attaching the handle to the head of the tool.

A hammer handle is conventionally secured to the hammer head by using opposite tapers and a wedge driven into the outer end in order to expand the same. This arrangement, although inexpensive and long-used, is not wholly satisfactory, and sometimes the head will fly off the handle during use. More frequently, the head may become loose on the handle, and to tighten it the head is hammered further onto the handle, thus tightening the fit at the inner taper, but unfortunately and necessarily, further loosening the fit at the outer taper.

The primary object of the present invention is to generally improve tools such as a hammer, ax, or pick.

A more particular object is to provide an effective and inexpensive method of attachment in which the end of the tool handle and the socket in the head receiving the same, will be matingly tapered with a taper running in only one direction. This provides a tight fit and avoids rocking or loosening of the head on the handle, provided that the handle is held against initial movement out of the mating socket of the head. A further object is to prevent such initial movement, and this is done by the provision of a nut in the handle receiving a screw on the head. Such an arrangement has heretofore been proposed, but has not proved practical, either because of the expense of building the desired construction into the tool, or because of failure to lock the screw against loosening under the vibration and impacts resulting from use of the tool, or because the provision of the necessary parts in the handle have weakened the handle, so that it was likely to break or split when subjected to an extra-heavy blow.

It is the specific object of the present invention to overcome the foregoing defects, and to provide a screw and nut arrangement for locking a tapered handle in a tool head, which arrangement will be inexpensive and self-locking, and which will not weaken any exposed part of the handle subject to breaking or splitting force.

To accomplish the foregoing general objects, and other more specific objects which will hereinafter appear, my invention resides in the tool and handle and attaching elements, and their relation one to another, as are more particularly described in the following specification. The specification is accompanied by a drawing, in which:

Fig. 1 is a partially sectioned side elevation of a part of a tool, embodying features of my invention;

Fig. 2 is an end view of the same;

2

Fig. 3 is a horizontal section taken approximately in the plane of the line 3—3 of Fig. 1;

Fig. 4 is a vertical section taken approximately in the plane of the line 4—4 of Fig. 1;

Fig. 5 is a vertical section taken approximately in the plane of the line 5—5 of Fig. 1; and

Fig. 6 is an exploded view showing the parts of the handle.

Referring to the drawing, and more particularly to Fig. 6, the tool handle 12 comprises a tapered end 14 and a U-shaped sheet metal nut 16 having a thread-engaging portion at the base 18 of the U. The end of the handle has cuts 20 receiving the arms of the U, and an anchor pin 22 passes transversely through the tapered end 14 of the handle, and through mating holes in the arms of the nut, in order to anchor the nut in the end of the handle.

The relation of the parts when assembled together, will be clear from examination of Figs. 1, 3 and 4 of the drawing, in which it will be seen how the arms 16 of the nut are locked in handle 12 by means of the pin 22.

The tool is here illustrated as a claw-hammer, the head 24 of which has a tapered socket which mates with the taper on handle 12. A cover plate 28 bridges across the outer or small end of the tapered socket, and a screw 30 passes through plate 28 into the nut. It will be evident that when the screw is tight, it prevents longitudinal movement of the handle out of the head of the hammer, thus maintaining the desired tight fit between the tapered handle and the tapered socket in the tool head.

The nut is preferably a self-locking nut. In the present case it is a so-called "speed nut," manufactured by Tinnerman Products, Inc., of Cleveland, Ohio. It is characterized by the provision of thread-engaging prongs 32 and 34 struck from the sheet metal body of the nut. These prongs differ from one another, for they engage the screw at points which are a half-pitch apart along the screw. The prongs are arched in such a way that when the screw is tightened, the prongs push deep into the root of the thread and are bent in such a way as to be self-locking. There are other self-locking nuts of this same general character made by other manufacturers. The nut is particularly well suited for the present purpose not only because of its self-locking characteristic, but even more because it can be anchored to the handle without appreciably weakening the handle.

Specifically, to receive the arms of the nut, it is merely necessary to provide thin slots such as those indicated at 20, 20 in Fig. 6. These are readily produced by a pair of saw-cuts. The pin 22 anchors the nut in the handle, and the assembly does not appreciably weaken the handle, because the slots for the nut and the hole for

the pin are all located in a part of the handle which is protectively housed within the head of the hammer. This is best shown in Fig. 1, in which it will be seen that the slots for the nut and the hole for the pin are localized in approximately half of the part of the handle that is driven into the head of the hammer, it being understood that the head includes the usual boss or shank portion 40. Some tool heads, for example an ax, do not have such an extension, but in that case the width of the ax blade is itself much greater than the width of a hammer, so that the same ample depth of socket is available to protectively enclose a substantial length of handle.

It is important to understand that the work load of the tool is not applied to the screw 30, and it is neither contemplated nor necessary that the nut and screw be designed to take the force of the hammer blows. Actually the load is taken wholly by the tight fit between the handle and the head. The mating tapers insure this result. The taper is preferably made slight, so that the wedging action between the handle and the head will be a very secure one. The only thing that it is necessary for the screw and nut to do is to inhibit any initial longitudinal movement of the handle relative to the head, for that would in turn loosen the fit between the tapered parts, and thereupon much of the work load would be applied to the screw.

In practical operation the tool may be used for a long time without any perceptible loosening of the parts. In the event, however, that loosening should occur, either because of long, hard use of the tool, or because of drying and shrinking of the wood, such looseness will be noticed by the person using the tool. He will thereupon hit the free end of the handle against a hard surface (as is now done with ordinary hammers), thus forcing the head tightly on the handle, following which the screw 30 will be tightened to hold the handle in its new tightened position. In Figs. 1 and 3 it will be noted that a space or clearance 42 is provided between the end of the handle and the cover plate 28, thus affording room for retightening the handle, as described.

It is believed that the construction and method of use, as well as the advantages of my improved method of attaching a tool handle to a tool head, will be apparent from the foregoing detailed description thereof. It will also be apparent that while I have shown and described the invention in a preferred form, changes may be made in the structure disclosed, without departing from the spirit of the invention, as sought to be defined in the following claims.

I claim:

1. In combination, a tool handle, a nut, and an anchor pin, said nut being a U-shaped sheet metal nut having self-locking thread-engaging prongs struck from the base of the U, the end of said handle having recesses receiving the arms of the U, and said anchor pin passing crosswise through the end of the handle and through mating holes in the arms of the nut in order to anchor the nut in the end of the handle.

2. A tool handle having a tapered end, a U-shaped sheet metal nut having a thread-engaging portion at the base of the U, the end of said handle having cuts receiving the arms of the U, and an anchor pin passing transversely through the tapered end of the handle and through mating holes in the arms of the nut in order to anchor the nut in the end of the handle.

3. A wooden tool handle having a tapered end, a U-shaped sheet metal nut having self-locking thread-engaging prongs struck from the base of the U, the end of said handle having cuts receiving the arms of the U, and an anchor pin passing transversely through the tapered end of the handle and through mating holes in the arms of the nut in order to anchor the nut in the end of the handle.

4. A tool comprising a head having a tapered socket, a handle having a matingly tapered end received in said socket, a U-shaped sheet metal nut having a thread-engaging portion at the base of the U, the end of said handle having recesses receiving the arms of the U, an anchor pin passing crosswise through the tapered end of the handle and through mating holes in the arms of the nut in order to anchor the nut in the end of the handle, a plate on said tool head across the small end of the tapered socket, and a screw passing through said plate into said nut in order to hold the tapered end of the handle tightly in the tapered socket.

5. A tool comprising a head having a tapered socket, a wood handle having a matingly tapered end received in said socket, a U-shaped sheet metal nut having self-locking thread-engaging prongs struck from the base of the U, the end of said handle having cuts receiving the arms of the U, an anchor pin passing transversely through the tapered end of the handle and through mating holes in the arms of the nut in order to anchor the nut in the end of the handle, a cover plate on said tool head across the small end of the tapered socket, and a screw passing through said plate into said nut in order to hold the tapered end of the handle tightly in the tapered socket.

6. A tool comprising a head having a tapered socket, a wood handle having a matingly tapered end received in said socket, a U-shaped sheet metal nut having self-locking thread-engaging prongs struck from the base of the U, the end of said handle having cuts receiving the arms of the U, an anchor pin passing transversely through the tapered end of the handle and through mating holes in the arms of the nut in order to anchor the nut in the end of the handle, a cover plate on said tool head across the small end of the tapered socket, and a screw passing through said cover plate into said nut in order to hold the tapered end of the handle tightly in the tapered socket.

7. A wooden tool handle having a tapered end, said end being rectangular in cross-section, a U-shaped sheet metal nut having self-locking thread-engaging prongs struck from the base of the U, the end of said handle having a pair of generally collateral saw-cut like cuts receiving the arms of the U, said cuts extending longitudinally of the handle and transversely of the long sides of the aforesaid rectangular section, said cuts extending entirely across the end of the handle, and an anchor pin passing transversely through the tapered end of the handle in the direction of the long sides of the aforesaid rectangular section, said pin passing through mating holes in the arms of the nut in order to anchor the nut in the end of the handle.

8. A tool comprising a handle as defined in claim 7, and a head having a tapered socket dimensioned to receive the tapered end of the handle, a cover plate on said tool head across the

small end of the tapered socket, and a screw passing through said cover plate into said nut in order to hold the tapered end of the handle tightly in the tapered socket.

9. A tool comprising a handle as defined in claim 7, and a head having a tapered socket dimensioned to receive the tapered end of the handle, a cover plate on said tool head across the small end of the tapered socket, and a screw passing through said cover plate into said nut in order to hold the tapered end of the handle tightly in the tapered socket, said nut and anchor pin being located in a part of the tapered end of the handle which is fully and protectively housed within the aforesaid tapered socket.
